J. J. CULLINAN

TENNIS RACKET

Filed April 17, 1922

Inventor,
John J. Cullinan,
By express sole Agent & Atty's.

UNITED STATES PATENT OFFICE.

JOHN J. CULLINAN, OF CHICAGO, ILLINOIS.

TENNIS RACKET.

Application filed April 17, 1922. Serial No. 554,326.

To all whom it may concern:

Be it known that I, JOHN J. CULLINAN, a citizen of the United States, and a resident of Chicago, in the county of Cook and State 5 of Illinois, have invented certain new and useful Improvements in Tennis Rackets, of which the following is a specification.

This invention relates to improvements in tennis rackets, and more especially to a new 10 and novel method of construction for rackets involving no distinct departure from the standard design and general formation thereof, but introducing an improved method of reinforcing and finishing the 15 racket by the use of gut.

The object of the invention is to provide a superior playing implement by the treatment of the racket frame in a way calculated to increase its strength, its ability to 20 maintain its true shape, and to resist warping, and to otherwise promote those qualities most desired in play.

In the drawings are disclosed the novel features of the invention, wherein

25 Figure 1 is a perspective view in elevation of a tennis racket embodying the invention.

Figure 2 is an enlarged detail view of a 30 portion of the edge of the racket head as taken on line 2—2 of Figure 1.

Figure 3 is an enlarged detail view in 35 longitudinal section through the throat of the racket and in the plane of the single gut strand, and

Figure 4 is an enlarged cross sectional view taken on line 4—4 of Figure 2.

Referring to the general features of the tennis racket, the accepted principles of construction have been followed; namely, 40 the combination of a relatively light head 1 of oval conformation, and a short stout handle 2, the head consisting of an open frame strung with a net work of tightly drawn and interwoven strings of gut forming the resilient impact area, or playing surface 4. The frame 3 is usually formed from a single strip of selected wood bent into shape, with the ends brought together to form the shoulders or portions 3^a 3^a of

45 slightly reversed curvature and the narrow neck portion of "throat" 5, which is continued into the handle 2, the latter being enlarged by the addition of light wood strips 6 extending lengthwise of the handle 50 and trimmed to provide a firm grip for the

hand. A leather strip or collar 7 is applied to the base of the handle to insure the firm grip and prevent the racket from slipping from the hand.

In order to avoid abrupt bends at the 60 throat of the racket, a wedge shaped member or throat piece 8 is inserted at the junction of the ends of the frame forming strip 3, these parts being securely joined together to form an almost unitary structure. The 65 throat piece gives added strength and reinforcement at this point, which ordinarily is the weakest point of the racket. Added strength and reinforcement at the throat is provided, at least in the better grade of 70 racket, by the application of a thin strip of wood or fiber 9 along the inner edge of the frame adjacent the throat. In the ordinary racket, a metal pin or rivet extends transversely through the parts forming the 75 throat for holding the same together, and resisting the inherent and applied forces, tending to separate or split the parts at this point.

The gut strings 10 are also threaded back 80 and forth through the frame 3 in a standard and approved manner, which need not be described in detail except to point out that the strings extend both lengthwise and crosswise of the racket head, each string 85 passing outwardly through an oblique hole 11, inclined toward one edge of the frame, and thence transversely of the outer edge of the frame to another hole 12, positioned in staggered relation to the first mentioned 90 hole and through which the string again passes through the frame to form another parallel string. In passing from hole to hole and obliquely of the edge of the frame, the strings lie within grooves, so that they 95 will be protected, with the result that the outer edge of the frame presents a zig-zag line of grooves connecting the lines of staggered holes. This, is common practice in racket construction, and yet is objectionable 100 for the reason that the contact of the strings with the wood develops a sawing action that contributes to the premature fracture of the strings.

Referring now to the more novel construction of rackets, the frame is provided 105 completely around its outer edge or face with a deep groove 13 substantially as wide as the distance separating the transversely spaced lines of holes 11, and 12. By virtue 110

of this circumferential groove, the short oblique grooves from hole to hole are eliminated. Inasmuch as the holes average into the single deep groove at the outer face of the frame. The groove 13 terminates a short distance down the sides of the throat portion connecting with an arrangement of transverse bores or holes through the throat, as will be presently described.

10 Located with the groove 13, and surrounding the frame 3, is a string or strand of "gut" 14, considerably larger in diameter or size than the ordinary racket strings, size $3/23$ or $1/8$ ". This strand is applied to 15 frame prior to the operation of stringing the racket with the gut strings, forming the impact surface, and for reasons that will be presently made manifest.

The ends of the encircling strands are 20 treated and anchored in the following manner. At each end of the groove 13, is an oblique hole 15 bored through the throat portion of the racket including the throat piece 8, these holes being offset in different, al- 25 though parallel planes, so that they do not intersect, but cross each other at substantially right angles, coming out on the opposite side, at a point a short distance below the point where they entered the throat. At 30 each point of exit of the holes, are bored another pair of oblique holes, each in the plane of the upper pair of holes and again crossing each other in different planes, and coming out on opposite sides of the throat 35 still further toward the handle and thereof again the bore is repeated, and a third pair of oblique holes 17, 17 are provided, the entire throat portion of the racket being thus traversed by a series of zig-zag holes, lying in 40 parallel planes, and each hole arranged at substantially right angles to the corresponding holes of the other series.

The ends of the strand 14 are then threaded through the two series of holes, the same 45 being preferably dipped in hot glue beforehand. Considerable pull is exerted in the operation in order that the tension on the strand shall be as great as is practical. The ends of the strand emerge from the last pair 50 of holes on opposite sides of the throat, and are then trimmed close to the surface, and finally a hot iron is applied to the end surfaces, or the same otherwise seared, so that integral heads 14^a 14^a are formed due to the 55 swelling of the substance under the effect of the heat. These heads act in the same manner as rivet heads, and serve to prevent the strand ends from pulling out or otherwise yielding longitudinally.

60 At this point of the operation the strand 14, tightly surrounds the head, and its ends are firmly anchored in the throat. The stringing of the gut strings is now carried out, it being observed that the holes 11 and 65 12 through the frame, which have been de-

scribed as arranged in staggered relation about the outer surface, are alternately disposed on opposite sides of the circumferential groove 13, in fact, the holes merge with the edges of the groove as shown in Figure 70 4. In stringing the racket the same method is followed as before pointed out, but instead of the wood and gut being in contact, the strings make the turn or bend from one hole to another obliquely across, and in contact with the circumferential strand 14. The manifest result is that the strings not only bear against the gut, but they engage the rounded periphery of the strand, and are practically, if not entirely free from contact 75 with the wood of the frame. It follows therefore that, by reason of the material as well as the contour of the strand 14, the reversing tendency is largely obviated and failure in this respect eliminated in the same 80 degree. 85

Another result of the stringing operation is to be noted. Owing to the reverse curvature of the frame member at the shoulder portions 3^a 3^a the strand 14 necessarily follows a tangent from the commencement of the portion of reverse curvature, to the holes in the throat, as shown in dotted lines in Figure 3, these portions of the strand being spaced outwardly from the surface of the frame member and lie exterior to the corresponding portions of the groove 13. In stringing the racket throughout this portion of the frame the several turns of string 10 pass around the strand, not only drawing them inwardly to the groove, but placing an additional tension on the strand sufficient to draw it to the desired degree of 90 95 100 tautness.

Some of the advantages of this method of 105 racket construction have been alluded to. The encircling strand obviously adds considerable strength to the head, maintaining it in true shape and resisting those influences which tend to warp the frame out of 110 shape. The anchoring of the ends of the strand in the manner described accomplishes two results. First, it provides a non-yielding and permanent anchorage for the tightly drawn encircling strand, and further provides a reinforcement at the throat of the racket, not only connecting the parts together at this point, but distributes the binding effect through a considerable length, if not entirely throughout the throat. Thus the 115 gut replaces the usual method fastening member, which is inserted through the throat at a single point. 120

Other advantages such as more perfect 125 balance, and more workman like appearance are advantages which naturally flow from the departure herein set forth. Obviously the general features embodying the invention may be variously modified without departing from the spirit of the invention and 130

for that reason I do not wish to be limited except in so far as the invention is specifically pointed out in the appended claims.

I claim as my invention:

- 5 1. A tennis racket or the like comprising an open frame head adapted to be strung with resilient strings, and a handle spliced with said frame and a strand of stout gut drawn tightly around said frame and its 10 ends extending transversely through the racket at the junction of the frame and handle and anchored against displacement.
- 15 2. A tennis racket or the like comprising a head consisting of an oval frame provided with a circumferential groove, a handle and a throat portion at the junction of the frame and handle and a strand of stout gut encircling said head and lying within said groove, and its ends passed transversely 20 through said throat portion from opposite sides and securely anchored therein.
- 25 3. A tennis racket or the like comprising a head consisting of a frame of fibrous material of oval shape, and a handle formed in part by the end portion of said frame, and a strand of stout gut encircling said head, the ends of said strand being tightly drawn through holes extending transversely through said frame at the junction thereof 30 with said handle and securely anchored therein.
- 35 4. A tennis racket or the like, comprising a head, a handle and a throat portion at the junction of said head and handle, and a strand of stout gut extending around said head, and within a groove formed in the outer face thereof, the end portions of said strand passing transversely through the 40 throat and firmly anchored therein.
- 45 5. A tennis racket or the like, comprising a head, a handle and intermediate throat portion, a strand of stout gut extending around said head, and within a groove formed in the outer face of said head, and terminating on opposite sides of said throat in holes extending transversely through said 50 throat, the end portions of said strand pass-

ing through said holes, and anchored therein.

6. A tennis racket or the like, comprising 55 a head, a handle and intermediate throat portion, a strand of stout gut extending around said head and within a groove formed in the outer face of said head, the end portions of said strand being drawn 55 through separate series of holes bored through said throat portion in zig-zag arrangement, and securely anchored therein.

7. A tennis racket or the like, comprising 60 a head, a handle and intermediate throat portion, a groove extending around the outer face of said head, and terminating adjacent the throat portion, and a series of zig-zag bores 65 extending transversely through said throat, and longitudinally thereof from the extremities of said groove, and a strand of stout gut passing around said head and lying within said groove, the end portions thereof being threaded through said bores and securely anchored therein. 70

8. A tennis racket or the like, comprising 75 a head, a handle and an intermediate throat, and a strand of stout gut threaded through a series of zig-zag bores extending throughout the length of said throat portion, and lying in parallel planes with the corresponding bores of each series arranged substantially at right angles to each other, and heads formed at each extremity of said strand. 80

9. A tennis racket or the like, comprising 85 a head, a handle and an intermediate throat, and a strand of stout gut having its free end portions threaded through a series of holes bored transversely through said throat from opposite sides thereof, and in zig-zag fashion toward said handle, the extremities of said strand being seared to form head substantially flush with the surfaces of 90 said throat.

In witness whereof I hereunto subscribe my name this 13th day of April, A. D., 1922.

JOHN J. CULLINAN.
